(57) **CLAIM**

The ornamental design for controller with DC brushless motor, as shown and described.

DESCRIPTION

FIG. 1 is a front elevation view of a controller with DC brushless motor showing our new design;

FIG. 2 is a rear elevation view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof.
